UNITED STATES PATENT OFFICE.

DAVID D. BUICK, OF DETROIT, MICHIGAN.

DESIGN FOR A WATER-CLOSET TANK.

SPECIFICATION forming part of Design No. 29,845, dated December 20, 1898.

Application filed November 22, 1898. Serial No. 697,196. Term of patent 14 years.

To all whom it may concern:

Be it known that I, DAVID D. BUICK, a citizen of the United States, residing at Detroit, in the county of Wayne and State of Michigan, have invented and produced a new and original Design for Water-Closet Tanks, of which the following is a specification, reference being had therein to the accompanying drawings.

- Figure 1 is a perspective view of the tank. Fig. 2 is a side elevation thereof.

A is a substantially rectangular body portion with rounded corners, having an inclined top B; C, a central panel in said top, and D

is a back plate having a margin E extending 15 beyond the body portion at the top and sides.

The leading feature of the design is the substantially rectangular body having the inclined top and the panel.

What I claim as my design is—

The design for a water-closet tank, substantially as herein shown and described.

In testimony whereof I affix my signature in presence of two witnesses.

DAVID D. BUICK.
